UNITED STATES PATENT OFFICE.

ERNEST M. ORLOW, OF MILWAUKEE, WISCONSIN, ASSIGNOR OF ONE-HALF TO
ARTHUR J. SCHMITT, OF MILWAUKEE, WISCONSIN.

REENFORCED FABRIC FOR GARMENT CONSTRUCTION.

Application filed November 15, 1924. Serial No. 750,139.

This invention relates to reenforced fabric for garment construction and is primarily directed to a reenforced coat front.

In coat fronts as heretofore made it has been the practice to attach the stiffening or lining material at the lapel only and not at the breast or shoulder with the result that relative shifting and sagging of the body portion of the garment with relation to the reinforcing or stiffening would occur.

Further than this, the diagonal stretching to which all woven goods are subject is not counteracted by the stiffening, and the coat soon bulges, wrinkles or is otherwise uneven over the portion which is most exposed with consequent unsightly results.

Further than this it has been impractical, heretofore, to stiffen the front of the coat beneath the arm in the region of the side seam. This unstiffened portion, therefore, very readily wrinkles and becomes unsightly.

This invention is designed to overcome the above noted defects, and objects of such invention are to provide a reenforced fabric which is particularly directed to coat fronts, which is so constructed that stretching diagonally of the weave of the fabric is wholly avoided.

Further objects are to provide a coat front construction in which the reinforcement or stitching is secured in an adequate manner throughout its extent to the body of the fabric, in which the diagonal stretching of the main body fabric is prevented by the reenforce itself, in which the body fabric is supported through the extent of the reenforce and is held against stretching or bulging at any portion thereof.

Further objects of this invention are to provide a stiffened coat front in which horizontal lines of stitching are employed to secure the stiffening to the coat front throughout its extent, and in which the stiffening is extended to adjacent the side seam beneath the arm.

An embodiment of the invention is shown in the accompanying drawings in which:—

The single figure is a fragmentary inside elevation of a partially formed coat front.

Referring to the drawings, it will be seen that the body portion 1 of the coat front is formed in the usual manner with the threads of the woven goods running vertically and horizontally. The stitching or reenforce 2 is

shaped in the appropriate manner, as shown in the drawings, and is positioned on the body portion 1 with the threads of the reenforce extending diagonally with reference to the weave of the body portion.

This stiffening 2 is extended to a point beneath the arm opening 3, as shown in the drawing, and such extended portion 4 projects to a point adjacent the side seam of the coat.

The reenforce 2 is secured to the body portion 1 by means of a plurality of parallel horizontal rows of stitching 3 which are preferably blind stitching to keep from showing on the front of the garment. These rows are sufficiently close together to make the reenforce and body portion 1 act as a single entity and prevent separation of one from the other in any portion of their extent. In other words the reenforce is securely attached to the body portion not only at its edges but throughout its extent.

Obviously, in forming a reenforced fabric of this general nature the two plies with the weave of one running diagonally with reference to the weave of the other may be secured by cementing or in fact in other ways than by stitching, as shown in the drawings.

However, it has been found in the actual practice of this invention that the relatively closely spaced horizontal lines of blind stitching form the most effective means of securing the reenforce to the body portion and have other characteristics which will be described hereinafter.

It is to be noted particularly that the body portion 1 is not permitted to stretch diagonally of its weave in view of the fact that the threads of the reenforce are non-extensible and are diagonally arranged with reference to the threads of the body portion. Thus unsightly stretching, bulging or wrinkling of the finished coat is wholly prevented.

Further, the closely arranged parallel rows of stitching form an adequate reenforcing of the body fabric throughout the breast, lapel and shoulder portion and beneath the arms adjacent the side seams where stretching is most conspicuous in ordinary types of coats.

It is to be particularly noted that the coat fronts ordinarily tend to flute or pucker along vertical rows. This fluting or pucker-
ing is wholly avoided by providing the hori- 110

zontal parallel rows of stitching which extend throughout the entire area of the re-enforce, and which project to a point adjacent the side seams so as to secure the extended portion 4 of the re-enforce in place. Thus the puckering along vertical rows or flutes are wholly avoided and also the relatively soft portion of the coat beneath the arm portion adjacent the arm seams does not exist in a coat constructed in accordance with this invention. This is readily apparent from the fact that the re-enforce is secured firmly to the body or main portion 1 of the coat front beneath the arm pits and adjacent the side seams by a continuation of the horizontal rows of stitching.

Although the invention has been described in considerable detail, it is to be understood that the invention may be variously em-

bodied and is therefore, to be limited only as 20 claimed.

I claim:

In a coat, the combination of a body portion formed of fabric with the threads running horizontally and vertically, a stiffener for the front thereof extending across the lapel to the arm pit and to the seam below the arm pit, said stiffener being formed of fabric with its threads running diagonally in all portions of the stiffener 30 both in the lapel and in the body portion, and horizontal lines of stitching attaching said stiffener to said body portion.

In testimony that I claim the foregoing I have hereunto set my hand at Milwaukee, 35 in the county of Milwaukee and State of Wisconsin.

ERNEST M. ORLOW.
